UNITED STATES PATENT OFFICE.

GEORGE F. SEYMOUR, OF SAN FRANCISCO, CALIFORNIA, ASSIGNOR TO
SAMUEL C. IRVING, OF SAME PLACE.

ADJUSTABLE PIPE-TONGS.

SPECIFICATION forming part of Letters Patent No. 538,601, dated April 30, 1895.

Application filed August 10, 1894. Serial No. 519,970. (No model.)

To all whom it may concern:

Be it known that I, GEORGE F. SEYMOUR, a citizen of the United States, residing in the city and county of San Francisco, State of California, have invented certain new and useful Improvements in Adjustable Pipe-Tongs; and I hereby declare the following specification and the drawings therewith to be a complete description of my improvements.

10 My invention relates to that class of adjustable implements whereby pipes of various diameters can be turned, and consists of a shank or stem with a fixed jaw and a movable jaw attached thereto, by means of links or plates crossing the main stem diagonally, and as nearly as possible in the line of strain, and held at various points from sliding, and against the working strain, by means of a detent or pawl engaging notches or teeth on the 15 main stem or shank, near the main or fixed jaw this pawl being held by a spring acting also on the pivoted jaw, so the implement can operate after the manner of a ratchet, the pawl provided with a thumb plate, so it can 20 be instantly disengaged and the movable jaws set to suit pipes of any size within the range of the implement.

The objects of my invention are celerity of adjustment in such implements, also to so 25 dispose the material as to avoid transverse strain on the members, especially a bending strain upon the main member A and thus increase their strength, reducing their dimensions, and consequent weight of the complete 30 implement.

Referring to the drawings, Figure 1 is a side view of one of my improved adjustable pipe-tongs. Fig. 2 is an edge view of the same. Fig. 3 is a side view of the head or main parts 35 when the jaws are distended to their extreme capacity. Fig. 4 is another side view in which the jaws are closed to fit the smallest pipe within their range. Fig. 5 is a detail showing more clearly the construction of the pawl by means of which the movable jaw is held.

Similar letters of reference are employed to denote corresponding parts in the different figures of the drawings.

The main stem A is made preferably of steel, 40 or if of iron is laid with steel at the serrated

faces B and C. The hinged jaw D is also made of steel, or steel laid on its face at E. The jaw D is made integral with the side bars F F that pass diagonally across the main stem A, and are pivoted on the studs G G that slide 55 in the slots H H.

Between the side bars F F is a pawl I pivoted at J, and extending back in the form of a thumb piece K, by means of which the pawl is raised or disengaged at N. Beneath the 60 thumb piece K, and pressing it upward, is a spring L resting on a cross bar M, attached to and forming a strut between the bars F F. This spring pressing upward or outward on the thumb piece K, and consequently downward 65 on the pawl point N, causes an upward or outward strain on the fulcrum J, and a turning strain on the pivot G of the bars F F, pressing the jaw D forward, as indicated by the arrows in Figs. 1, 3 and 4, producing 70 in that direction an elastic pressure tending to keep the serrated faces E and B in contact with a pipe, and permitting a ratchet action, so that by moving the handle O through even a short arc the jaw will release and engage 75 automatically, and pipes can be turned in narrow places difficult of access.

By pressing down the thumb piece K, and disengaging the pawl point N, the jaw D can be slid outward to the position shown in Fig. 80 3, or inward to the position shown in Fig. 4, the pawl I engaging the notches at C, and thus adapting the implement to pipes of diameters varying as the dotted diagrams P and Q in the two figures named, or to any 85 intermediate point as the notches at C will permit or determine.

Referring to Fig. 3 of the drawings it will be seen by the points of contact on the pipe P that the principal strain will fall on the line 90 x-x, or approximately parallel to the bars or plates F F, also approximately with the pawl I, and thus avoid transverse strain on the various members of the implement.

Having thus explained the nature and objects of my invention, what I regard as new, and desire to secure by Letters Patent, is—

1. In a pipe-turning implement, as herein described, a main stem, and a pivoted jaw sliding thereon, the latter formed integrally 100

with links or bars crossing the main stem diagonally, in the line of principal strain, and between said links or bars a pawl that engages the main stem near its end and the jaw thereon so as to avoid bending strain upon the main stem, in the manner substantially and for the purposes described.

5. 2. In an implement of the class described, the combination of a main stem serrated at 10 the end to form a jaw and notched at the side, a pawl engaging said notched side, the links or bars that cross the main stem diagonally and in the line of principal strain and are formed integrally with a pivoted sliding jaw, 15 the aforesaid pawl being pivoted between the said links, substantially as described.

3. In a pipe-turning implement, as herein described, a main stem and sliding jaw, the latter formed integrally with side links that 20 have pivots sliding in recesses formed in the sides of the main stem; and between these links a pivoted pawl engaging the main stem

near its end and the jaw thereon so as to hold these sliding pivots and the movable jaw at various points, and adapt the implement to 25 pipes of different size, in the manner substantially and for the purposes specified.

4. In a pipe-turning implement, as herein described, a main stem and a pivoted sliding jaw thereon, the latter held by links or bars 30 crossing the main stem diagonally, and provided with a pawl and thumb plate, in the manner shown; a spring to hold the pawl engaged, and also exert a closing strain on the movable jaw so it will remain in contact with the 35 pipe to be turned, in the manner and for the purposes substantially as described.

In testimony whereof I have hereunto affixed my signature in the presence of two witnesses.

GEORGE F. SEYMOUR.
